UNITED STATES PATENT OFFICE.

THOMAS L. RAY, OF FORT WORTH, TEXAS.

ANALGETIC BANDAGE.

SPECIFICATION forming part of Letters Patent No. 699,897, dated May 13, 1902.

Application filed April 9, 1901. Serial No. 54,989. (No model.)

To all whom it may concern:

Be it known that I, THOMAS L. RAY, a citizen of the United States, residing at Fort Worth, Texas, have invented a new and useful Analgetic Bandage for Curing Headaches and other Disorders of the Nervous System, of which the following is a specification.

This invention relates to appliances for regulating the flow of blood about the head, whereby headache, insomnia, fever, and other disorders may be cured.

The object is to construct a suitable bandage for treating patients—a bandage which will not be cumbersome or inconvenient to the wearer.

Other objects and advantages will be fully described and set forth in the following description and more particularly pointed out in the claims.

Reference is had to the accompanying drawing, which forms a part of this specification.

The figure is a perspective view.

The bandage is provided with two pads A and B, which are attached to a strap E by means of tacks F or by any other suitable means. The pads are preferably elliptical in shape. Buckles G are placed on the strap E, and the ends of the strap are passed through rings H and attached to the buckles. Straps J and K are attached to the rings H, a buckle M being attached to the strap K and holes being made in the strap J, by which the buckle engages that strap. The rings H are provided, so that the strap will not pass across the ears of a person, the rings being large enough to encompass the ears without touching the same. A wider strap P is provided for placing between the straps J and K and the forehead, the strap P serving as a cushion. Loops R are attached to the strap P, and the straps J and K are passed under the loops, so that the strap P will not be displaced.

This bandage is placed on the head with the pads A and B pressing on the vasomotor

nerve centers at the base of the skull or in 45 the upper part of the back of the neck.

Having fully described my invention, what I claim as new, and desire to secure by Letters Patent of the United States, is—

1. A bandage consisting of straps adapted 50 to circumscribe the head and having a cushion and pads attached to the inside thereof, and means for protecting the ears from the pressure of the straps, said straps being provided with suitable buckles whereby said 55 pads may be adjusted to press on the nerve centers about the head for controlling the flow of blood through the head and the face.

2. A bandage provided with straps adapted to circumscribe the head, pads attached to 60 the inside of the strap passing around the lower back part of the head at points adjacent to the vasomotor nerve centers at the base of the skull, and rings circumscribing the ears for protecting the ears from the pressure of said straps, said straps being attached 65 to said rings.

3. A bandage comprising a strap adapted to pass around the lower back part of the head and having two pads attached to the inside thereof adjacent when in position to the vasomotor nerve centers at the base of the skull, a ring circumscribing each ear, said strap adapted to press said pads against the head and being adjustably attached to said 70 rings and connected together in front of the forehead whereby said straps hold said rings in place and draw said pads against the head, and a forehead-strap slidably mounted on the inside of said straps for protecting the 75 forehead from said straps.

In testimony whereof I set my hand, in the presence of two witnesses, this 4th day of April, 1901.

THOMAS L. RAY.
